UNITED STATES PATENT OFFICE.

JOHN S. SEARS, OF NEW YORK, N. Y.

DESIGN FOR A TOY BALLOON OR SIMILAR ARTICLE.

52,352.

Specification for Design.

Patented Aug. 27, 1918.

Application filed December 1, 1916. Serial No. 134,528. Term of patent 7 years.

To all whom it may concern:

Be it known that I, JOHN S. SEARS, a citizen of the United States of America, and a resident of the borough of Manhattan, city, county, and State of New York, have invented a new, original, and ornamental Design for a Toy Balloon or Similar Article, of which the following is a specification, reference being had to the accompanying drawing, which shows my new design applied by way of example to a toy balloon, Figure 1 being a front view and Fig. 2 being a side view thereof.

While I have shown my design embodied by way of example in a toy balloon, I want it to be understood that the application of the design is not limited to toy balloons, as the design may obviously be embodied in various other articles of manufacture, such as children's rattles. It is to be understood that my claim includes all substantial equivalents of my design as shown and described.

I claim:

The ornamental design for a toy balloon or similar article, substantially as shown.

JOHN S. SEARS.
